Primary Examiner — Leanne Was-Engelhart(74) *Attorney, Agent, or Firm* — Tsz Lung Yeung**CLAIM**

The ornamental design for a remote control outlet, as shown and described.

DESCRIPTION

FIG. 1 is a perspective view of a remote control outlet showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The drawings contain a symbolic break. The portion between the break lines form no part of the claimed design. The broken lines in the drawings showing portions of the remote control outlet that form no part of the claimed design.

1 Claim, 7 Drawing Sheets(56)
